UNITED STATES PATENT OFFICE.

EDGAR A. GILLINDER, OF PHILADELPHIA, PENNSYLVANIA.

JAR FOR PRESERVES, &c.

1,296,283.

Specification of Letters Patent.

Patented Mar. 4, 1919.

Application filed April 15, 1918. Serial No. 228,571.

To all whom it may concern:

Be it known that I, EDGAR A. GILLINDER, a citizen of the United States, residing in the city and county of Philadelphia, State of Pennsylvania, have invented a new and useful Jar for Preserves, &c., of which the following is a specification.

My invention consists of a jar of the order of a fruit, vegetable, packing or other jar having in the neck portion thereof a seat for the cover of the jar, and other means adapting a pad of paraffin or waxlike material to be imposed on said cover and be peripherally interlocked with said neck so as to control the cover in position and hermetically seal the joint of the cover with its seat and adjacent portion of the neck.

It consists also in providing the cover with a handle with which the central portion of the pad may interlock thus providing means for retaining the pad in position additionally to the interlocking of said pad or seal on its peripheral portion with the neck of the jar.

25 The invention is satisfactorily illustrated in the accompanying drawing but the important instrumentalities thereof may be varied, and so it is to be understood that the invention is not limited to the specific details shown and described, as long as they are within the spirit or scope of the claims.

Figure 1 represents a vertical section of a preserve jar embodying my invention.

Fig. 2 represents a top or plan view thereof.

Fig. 3 represents a horizontal section on line 3—3 Fig. 1, looking downward.

Similar numerals of reference indicate corresponding parts in the figures. Referring to the drawings:

1 designates the body of the jar, and 2 designates the neck thereof, the jar being formed of glass or other vitreous or equivalent material. On the inner side of said neck is the outturned channel, and below the same is the inwardly extending horizontal shoulder 4, which is of less diameter than the diameter of the interior of said neck. The shoulder 4 consists of upper and lower walls which are joined on their inner ends by a curved bend which presents no raw edge on the interior of the neck of the jar and prevents chipping of the inner edge of the shoulder. Again, said shoulder is formed by inwardly crimping the glass of said neck while yet hot from the exterior of the latter

after the interior of said neck has been blown, which as is evident is without shoulder, the latter being incapable of being blown or molded from within the jar 60 into shape.

Then said shoulder is formed by inwardly crimping the glass as has been stated, thus producing said shoulder of two walls, viz: the upper one on which the peripheral portion of the cover is seated, and the lower wall which sustains the inner end of said upper wall and then joins the portion of the neck below the outer end of said upper wall, said double walls thus forming the shoulder 70 of great strength.

5 designates the cover of the jar, the same having thereon the knob like member 6 which rises centrally therefrom and comprises a handle for the cover, the top edge 75 of said knob like-member being flush with the top edge of the neck, said cover and handle being integral of glass or other vitreous or equivalent material, said cover being of less diameter than the interior diameter of the neck so as to be capable of being passed through the latter and be placed upon the shoulder 4.

On the top of the cover is the pad 7 of paraffin, wax or other suitable material the 85 same comprising a seal and closure for the cover.

After the jar is supplied with an article to be preserved or packed, the cover is introduced through the neck and seated on the 90 shoulder 4, the periphery of said cover then being inclosed by the vertical wall 8 of the shoulder 4.

Paraffin, wax, or other material of the kind in suitable plastic condition is now 95 poured into the neck and spread over or pressed upon the upper side of the cover 5, so as to completely envelop the same forming the pad 7, the peripheral portion of which occupies the channel 3, thus interlocking said pad with the neck of the jar. The channel 3 is formed by outwardly crimping the neck of the jar from within the same, thus preserving the thickness of the glass in said crimp the same as in the remainder 100 of the neck, and consequently imparting strength to the wall of said channel since the crimp is a corrugation both internally and externally and so provides a reinforced connection for the upper and lower portions of the neck.

Again the exterior of the base of the knob

or handle is undercut or reduced in diameter so that the wall of the opening in the central portion of the pad encircles the same and is prevented from rising on the flaring portion of said knob, it interlocking therewith somewhat of the order of a dovetailed joint, whereby the pad is doubly controlled viz., peripherally and centrally, thus effectively retaining the cover on the shoulder 10 4, preventing its displacement therefrom and hermetically sealing the joint of the cover, the wall 8 and the shoulder 4, thus tightly closing the jar whether it is in the position shown in Fig. 1, or is in an inverted 15 position, which latter is practised in some cases. In said inverted position the top edge of the knob like-member which is now below will rest on the table, shelf, or other place of location of the jar flush with the top 20 edge of the neck, or mouth proper of the jar, and the weight of the jar and its contents causes said knob to press the cover 5 firmly upward on its seat centered from said knob whereby the sealing of the jar as inverted is 25 assured.

In order to open the jar the pad is removed, when the cover is free so that it may be lifted from its seat on the shoulder 4, and then withdrawn through the neck 2, 30 when the contents of the jar are accessible. It will be noticed that the upper portion of the knob-like member is entirely above and so removed from the pad 7, whereby it remains uncovered free to be grasped by the 35 fingers for handling purposes.

In practice the cover 5 is simply a flat circular disk or plate of glass, porcelain, or similar material, and so is inexpensive in construction and easily applicable and 40 movable, it being nicely retainable in closed position by the pad imposed thereon and obviates the use of threads, screw caps, or the like on jars or receptacles of the class.

Having thus described my invention 45 what I claim as new and desire to secure by Letters Patent, is:-

1. A preserve jar having a neck provided with a crimp extending inwardly from the exterior thereof forming a double-wall-inturned shoulder, a crimp extending outwardly from the interior of the neck forming an outwardly extending channel, a cover for the jar having its peripheral portion adapted to be seated on the upper wall of 50 said shoulder, and a sealing pad on said 55 said shoulder, and a sealing pad on said cover having its peripheral portion adapted to be seated in said channel, said cover having a handle-like member which rises there-

from and is adapted to have its top edge flush with the top edge of the mouth of the jar whereby when the sealed jar is inverted it will rest flat on both said top edge of the mouth of the jar and said top edge of the handle-like member.

2. A preserve jar having a neck provided with a crimp extending inwardly from the exterior thereof forming a double fall inturned shoulder, a crimp extending outwardly from the interior of the neck forming an outwardly extending channel, a cover for the jar having its peripheral portion adapted to be seated on the upper wall of said shoulder, and a sealing pad on said cover having its peripheral portion adapted to be seated in said channel, said cover having centrally thereon a knob-like member whose base is undercut forming a dovetail with which the center of said pad interlocks, the portion of said member above said undercut being free of said pad and exposed for handling.

3. A preserve jar having a neck provided on its interior with an inturned shoulder and an outturned channel, a cover adapted to be seated on said shoulder, a sealing pad 85 adapted to be seated on said cover and having its peripheral portion fitted in said channel, and a knob-like member rising centrally from said cover through said pad, the base of said member being undercut and having 90 said pad interlock with the same, the upper portion of said member being removed from said pad and left uncovered for handling the cover.

4. A preserve jar having a neck provided with a crimp extending inwardly from the exterior thereof forming a double wall inturned shoulder, a crimp extending outwardly from the interior of the neck forming an outwardly extending channel, a cover for the jar having its peripheral portion adapted to be seated on the upper wall of said shoulder, and a sealing pad on said cover having its peripheral portion adapted to be seated in said channel, said cover having centrally thereon a knob-like member whose base is undercut forming a dovetail with which the center of said pad interlocks, the portion of said member above said undercut being free of said pad and exposed for handling, said 105 member having its top edge flush with the top edge of the mouth of the jar.

EDGAR A. GILLINDER.
